(57) **CLAIM**

The ornamental design for a “food service tray,” as shown and described.

DESCRIPTION

FIG. 1 is a perspective view of the food service tray;
 FIG. 2 is a top plan view of the food service tray;
 FIG. 3 is a bottom plan view of the food service tray of FIG. 1;
 FIG. 4 is a front elevational view of the food service tray of FIG. 1;
 FIG. 5 is a back elevational view of the food service tray of FIG. 1;
 FIG. 6 is an elevational view of one end of the food service tray of FIG. 1; and,
 FIG. 7 is an elevational view of the end of the food service tray opposite the end shown in FIG. 6.
